UNITED STATES PATENT OFFICE.

WILLIAM E. HOKE, OF BALTIMORE, MARYLAND.

APPARATUS FOR FINISHING HIGH-GRADE GEARS.

Application filed January 11, 1924. Serial No. 685,686.

This invention relates to a method of and apparatus for accurately finishing gears.

In the manufacture of gears, particularly those used in automobile transmission, it has heretofore been the practice to machine and harden the gears and in addition to subject them to a finishing process termed, "wearing them in." The purpose of this process is to eliminate roughness, which would result in 10 noisy operation.

In some instances gears to be finished or worn in are merely put in mesh and subjected, a suitable abrasive being applied, to an adjustable load. In other instances a 15 gear to be finished is lapped by being meshed with a gear of softer material, such as cast iron. This latter method is based on the theory that the abrasive used in all cases embeds itself in the softer metal and wears 20 away the harder metal.

It also has been proposed to systematically wear in gears by causing two gears to be finished to wear against each other and thereby mutually correct each other.

25 However, also these methods rely on a more or less fortuitous wearing action.

It is a general object of this invention to provide a method of and an apparatus for wearing in and truing gears, and producing 30 gears having teeth concentric, equally spaced, and with conjugate surfaces.

Another object is to provide an apparatus by means of which the wearing-in operation may be performed in less time than has heretofore been possible.

Briefly stated, the invention in its broader aspect consists in making a gear or gears to be worn in a part of a closed gear train, then adjusting the elements of the gear train relatively to each other in any of many ways suitable or by any of many means available for taking out the back lash and establishing, at will, any desired pressure reaction of the gears upon each other then subjecting the 40 gear to be worn in to a continued abrasive action, which may be produced by causing an abrasive to act upon the gear, as for instance, through the agency of alapping gear

forming likewise a member of the train, while operating the train, and gradually adjusting the pressure reaction between the gears to maintain a desired wearing load until the operation is completed. 50

The invention and the principle of operation upon which it is based may be fully 55 understood from the specification of which the accompanying drawings are a part.

In the drawings:

Fig. 1 is a plan view of an arrangement embodying the invention; 60

Fig. 2 is an elevation thereof;

Fig. 3 is a plan view of an arrangement showing another application of the invention;

Figs. 4 and 5 are a plan view and a side 65 view diagrammatically representing another modification;

Fig. 6 is a diagrammatic plan view explaining the principles of operation;

Figs. 7 and 8 are a plan view and a section respectively of another modification; 70

Fig. 9 is a more or less diagrammatic view showing another mode of applying the principles of the invention; and

Fig. 10 is a more or less diagrammatic 75 view showing a modification thereof.

Assume that the gears 10, 11, 12 and 13 in Fig. 1 are gears to be worn in and trued, I use a toggle link system in which the links 14, 15, 16 and 17 are pivotally interconnected by the shafts 18 of the gears. The different links have each a length from pivot to pivot corresponding substantially to the distance from the center of one gear to the center of another gear fully in mesh with it. 85

For the sake of mechanical rigidity I prefer to use between the same studs a plurality of links in spaced relation as indicated in Fig. 2.

When the gears are mounted on their respective shafts, they form an interlinked gear train or a gear train closed upon itself. When the toggle link is in what may be called a neutral position, each gear has a certain amount of play, commonly referred to as "backlash," relatively to the adjacent 90

gears and the whole train has a certain amount of play. When pressure is applied to the link system inwardly from opposite corners, this backlash is taken up, which means that all teeth of the gear train that may at any time be in mesh, are in definite forced contact relation whether the gear train operates in one direction or in the opposite direction, in the sense that like sides of all the teeth of any one of two mating gears are successively engaged by like sides of the teeth of the other gear, while the remaining sides of the teeth of the same two gears are not in wearing contact with each other. When pressure is applied from the other opposite corners of the link system, the play is likewise taken up, but the relativity of forced contact points is reversed, which means that contact between the 20 successively interacting teeth of any two gears takes place on that side of each tooth which was previously out of wearing contact.

When, after pressure was applied in one diagonal, pressure is applied in the other diagonal, contact between the teeth of two gears is thrown from one side to the other side of the teeth.

The significance of this feature is as follows:

Since there is always a certain amount of play between gears, the teeth of two gears in mesh with each other will normally accommodate themselves according to conditions. Assume that the teeth of a pair of meshing gears are imperfectly spaced or have some other imperfection which must be worn off in order to obtain a silent gear. During the usual "wearing-in" operations as soon as the imperfection on one gear comes into contact with a tooth on the other gear, a slight relative angular movement will take place between the two gears tending to take up the play. In other words, the driven gear yields to the driving gear.

With the arrangement described, the play can be initially taken up and any unevenness or rough spot is subjected not merely to the wearing action of a force corresponding to the load carried but also to the grinding action of the opposing teeth which follow rigidly a prescribed path. When the rough spot assumed comes into contact with a tooth on the opposing gear, neither of the gears can yield forwardly or rearwardly as the case may be, because there is no play. If the meshing teeth happen to be of correct form, there is, of course, no lapping action, because there is no pressure exerted. It will be understood that a suitable abrasive is used to cause the necessary grinding action.

Many gears run noiselessly at light load but become noisy under heavy load. This is attributed to the bending of the teeth under

load which causes the points of the adjacent teeth to strike when they in turn come into contact. In order to avoid this, many manufacturers make teeth of a modified involute curvature, the modification consisting in a 70 dubbing off slightly the ends so that the teeth do not strike but come into contact gradually with a sliding movement, as they should. This modification has been entirely empirical heretofore. By the arrangement 75 proposed the dubbing off is done naturally and effectively by the arrangement described by controlling the load conditions.

The pressure or load may be applied as indicated or in any other equivalent manner. 80 At diametrically opposite points of the link system the shafts carrying the gears may be connected to bars 19 and 20 having bearings for the shafts. One of the bars may be held stationary by any suitable means while the other shaft may be movably supported. As indicated, pressure may be applied in opposite directions by turning nuts 21 and 22 on the screw-threaded shank of bar 23 against an abutment 24. When the nut 22 is loosened and the nut 21 turned up against the abutment 24, the pressure is applied inwardly. When the nut 21 is loosened and the nut 22 turned up against the abutment, the pressure is applied outwardly. 95

By this arrangement the gears may be held in a neutral position without load or the play may be taken up and pressure applied to furnish an artificial load. The points of contact may be shifted from one side to the other, as above explained, without changing the direction of rotation. 100

The length of the links may be made adjustable for the purpose of varying from time to time the intercenter distance and thereby the amount of overlap. 105

In the drawing the mode of applying pressure is merely intended for the purpose of illustration. In practice mechanism may be provided for quickly changing the direction of the application of pressure, as for instance a lever arrangement similar to gear shift levers, coupling operating levers or clutch operating levers, whereby the pressure may not only be quickly varied but also reversed. 110

The gears represented in Figs. 1 and 2 have 54, 50, 45 and 40 teeth respectively. As is well understood, in case two gears have the same number of teeth the same teeth will always come into contact with each other. In cases where they have a different number of teeth, the same teeth will come into mesh again only after two or more revolutions. For instance, as to the two gears having 45 and 40 teeth respectively, after eight revolutions of the former and nine revolutions of the latter the same teeth come again into contact. In order to bring all or at least a larger number of teeth in contact with each other, it is advisable to angularly turn from 115 120 125 130

time to time one gear relatively to the other. With the arrangement as above described, it is a simple matter to change the position.

Gears, the number of teeth of which have 5 no common factor and whose teeth differ only by a small number, need not be turned as often as other gears. Gears which run on the hunting tooth principle, as for instance a gear having 49 teeth and another 10 50 teeth, need of course not be angularly turned at all. It is merely emphasized that where turning is desirable, it may be readily and quickly accomplished.

The more completely the interengagement 15 of the teeth is varied, i. e. the more different teeth are brought into mesh with each other, the more uniform will be the teeth after the operation.

The mode of operation described applies, 20 of course, also to compound gearing, for instance a shaft carrying a gear and a pinion, it being merely necessary to suitably modify the link arrangement and make such other minor changes as may be found desirable for 25 the purposes of the invention. It applies to gears of all kinds, viz: bevel gears, spur gears, spiral gears, herringbone gears, etc.

Fig. 3 shows an application of the invention for wearing in bevel gears. In the particular example is disclosed a typical arrangement including two bevel bears 25 and 26 and two pinions 27 and 28 forming a gear train closed upon itself. The shafts 29 and 30 of the pinions are mounted in yoke links 31 and 32 which are pivotally interconnected through the shafts 33 and 34 of the gears 25 and 26, respectively, as pivots. When pressure is applied to move one of the yokes, while the other is held stationary, motion 40 of the link which is moved takes place about the axes of the gears 25 and 26. The links might of course be pivoted in the shafts of the pinions and connected to the shafts of the gears. The effect is the same in one case 45 as in the other. It is merely necessary that the gears are relatively movable one about the axis of another in mesh with it and that the intercenter distance is maintained constant.

Figs. 4 and 5 show an application of the invention for wearing in compound gears. The compound gears comprising a gear 35 and a pinion 36 on shaft 37, on the one hand, and a gear 38 and a pinion 39 mounted on a 50 shaft 40 on the other hand, are in mesh with lapping gears 41 and 42 respectively to constitute a gear train closed upon itself. The shafts 37 and 40 may be suitably interconnected with the shafts 43 and 44 of the lapping gears by a link connection similar to that shown in Figs. 1 and 2. To avoid complication of the drawing this link mechanism is not shown, the relative movement of the shafts being indicated by the arrows. 60

It is understood that the lapping gears 41

and 42 must have the proper ratio of gears in correlation to the compound gears to make the arrangement operative.

The lapping gears may be considerably wider than the gears to be worn in, in order 70 that axial movement may be imparted, thus hastening the wearing in and distributing the wear on the lapping gear.

The principle of operation is more clearly illustrated in Fig. 6 in which individual gear 75 teeth are represented as being the ends of bell crank levers 45, 46, 47 and 48. Relative movement of the shafts 49 and 50 of levers 45 and 46 respectively toward each other, will take out all play in the system. Assuming that normally there is a slight play 80 between the four pairs of teeth, the levers 47 and 48 can be moved outwardly from the line passing through the shafts 49 and 50, while the shafts 49 and 50 are moved toward 85 each other so that the intercenter distances remain the same. This relative movement can take place only until the four pairs of teeth are firmly in contact with each other. The relative movement is the same whether 90 the levers 45 and 46 are moved away from each other. A like bell crank system including, however, the teeth 51, 52, 53 and 54 would differ from the one shown only as to the relativity of contact. By moving the 95 levers 47 and 48 toward each other the ends thereof representing the teeth would make contact on their opposite sides as compared with the illustration of Fig. 6. This shows clearly the mode of operation of shifting 100 contact of the teeth to relatively opposite sides while taking up the play when one or the other group of diametrically opposite gears is moved.

The shifting can of course be produced, as 105 indicated in Figs. 1 and 2 by holding one shaft stationary and moving the opposite shaft either toward or away from the stationary shaft. The movement of the other shafts must necessarily be outwardly and 110 inwardly respectively.

The significant feature of the arrangement is that the gear train closes upon itself, i. e. that any power impressed upon one gear is transmitted through all gears of the 115 train and reacts upon the former. All energy expended is therefore made useful in the train. The train constitutes its own load and the forces are equally distributed throughout the train, making for uniformity 120 and accuracy.

In the foregoing I have maintained the gears in a fixed intercenter relation by means of links interconnecting the gear shafts or studs. This arrangement has certain 125 advantages, but within the broader aspect of the invention no links are necessary.

In Figs. 7 and 8, for instance, the studs 61, 62, 63 and 64 may be mounted in a table 60. The holes 65 in which the studs 61, 62,

and 63 are disposed are preferably slightly larger than necessary to accommodate the studs. The studs include each a flange 66 bearing upon one face of the table while a washer may be interposed between the nut 67 and the other face of the table. Each shaft thus may be clamped in any desired position within the limited range of adjustment.

16. The stud 64 is mounted in a slide 68 which is movable in a slot 69. By means of screws 70 and 71 the slide may be moved in the slot. The portion 64^a is preferably eccentric to facilitate angular adjustment.

17. The operation is as follows:

The studs 61, 62 and 63 are adjusted on the table and clamped in desired position. A gauge 72 may be applied for facilitating the adjustment. The stud 64 is clamped to the slide 68 in any desired angular position of portion 64, and the slide is moved inwardly or outwardly until the back-lash is taken up. In practice the slide 68 is gradually moved while the gears are in rotation so that a buck tooth in the gear train cannot do any damage. Then progressively, as the wearing-in operation proceeds, the slide can be farther adjusted to take up the back-lash caused by the wear.

18. The forms of construction shown in Figs. 9 and 10 differ from the other forms disclosed by the use of racks for completing the gear train or closing the gear train upon itself.

19. In Fig. 9 two gears 73 and 74 of different size are in engagement with racks 75 and 76. The two gears are adjustable relatively to each other by means of links 77 and screws 78. When the studs or shafts on which the gears are mounted are moved either toward each other or away from each other, the back-lash is taken up to any desired extent. Either rack may be reciprocated, the other, preferably, being held stationary.

20. In the form shown in Fig. 10 a single rack 79 is used to close a gear train upon itself. The back-lash is eliminated by movement of the gear 80 inwardly toward, or outwardly away from, the rack. The two gears are adjustable relatively to each other by means of links 90 and screws 91.

21. It is evident that the racks 75 and 76 in Fig. 9, and the rack 79 in Fig. 10, are each the equivalent of a gear. In the claims the term "gear" is therefore intended to include not only all forms of gear mechanism by which a train of gears can be closed upon itself, but also racks which are to be considered as gears of infinite radius.

22. While each form of construction described includes a gear train closed upon itself, i. e. a gear mechanism in which the transmission may be considered as starting from the teeth of any one member and leading back to the teeth of the same member, I am aware that

the invention may be carried out in other ways and by different arrangements. Within the broader aspect of the invention any construction by which a gear may be subjected to a wearing-in action while back-lash is prevented is available for the purposes of the invention. I have disclosed various arrangements which I consider as particularly well suited solely in order to explain the novel line of action and the new principle 75 in contra-distinction to the methods heretofore used.

I claim:

1. Apparatus for wearing in gears, comprising means for mounting the gears to form a gear train closed upon itself and means for bodily adjusting one of the elements of the gear train relatively to the adjoining gears in mesh with it to eliminate back-lash in the train. 80

2. Apparatus for wearing in gears, comprising means for maintaining a plurality of gears in a substantially fixed angular relationship forming a gear train closed upon itself, means for permitting a slight bodily adjustment of one of the gears relatively to the adjoining gears in mesh with it to eliminate back-lash and means for maintaining said adjustable gear in any desired adjusted position. 90

3. Apparatus for wearing in gears, comprising means for mounting the gears to form a gear train closed upon itself and means for permitting relative bodily adjustment to change the angular relation of the gears and for maintaining constant the intercenter distance between gears which are in mesh with each other. 100

4. Apparatus for wearing in gears, comprising a plurality of shafts adapted to support a plurality of gears in the form of a gear train closed upon itself and a link system interconnecting the shafts for permitting each gear to be angularly adjustable relatively to the axis of the adjacent gear in mesh with it and for maintaining the intercenter distance between meshing gears constant. 105

5. The combination of a gear train closed upon itself and a link system interconnecting the gear shafts for permitting relative angular movement of each of two intermeshing gears about the axis of the other and maintaining the intercenter distance between intermeshing gears constant. 115

6. The combination of a gear train closed upon itself and a toggle link system interconnecting the gear shafts. 120

7. Apparatus for wearing in bevel gears, comprising two shafts mounted in axial alignment and a plurality of shafts disposed at right angle thereto, the arrangement being adapted to support two bevel gears opposite each other and a plurality of bevel gears in mesh therewith and means for adjustably 125

supporting the shafts of the intermediate gears for angular movement about the aligned shafts.

8. Apparatus for wearing in gears, comprising means for mounting the gears to form a gear train closed upon itself, means for permitting a slight relative adjustment of each pair of adjoining gears, means for

permitting bodily movement of one of the gears symmetrically relatively to its adjoining gears and means for maintaining the said gear in a definitely adjusted position.

In testimony whereof, I affix my signature.

WILLIAM E. HOKE.
